Attorney

UNITED STATES PATENT OFFICE

JOSEPH DROPULICH, OF HOUSTON, PENNSYLVANIA

CHECK HOLDER FOR MINE DUMP CARS

Application filed November 28, 1930. Serial No. 498,810.

This invention relates to a check holder for mine dump cars and has for an important object to provide, in a manner as hereinafter set forth, a device of this character embodying a novel construction and arrangement of parts whereby a check which is inserted and retained therein by gravity so long as the device is in vertical position will be discharged by gravity when the holder is disposed at an angle, as when the car is dumped, the holder being rigidly mounted on the car.

Another important object of the invention is to provide a check holder for mine dump cars embodying a pair of pivotally mounted spring controlled jaws for releasably retaining the check in the discharge opening of the holder in a manner to permit the check to be conveniently removed by hand.

Other objects of the invention are to provide a check holder for mine dump cars of the character described which will be simple in construction, strong, durable, efficient in its use and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view principally in vertical longitudinal section through a check holder for mine dump cars constructed in accordance with this invention.

Figure 2 is a vertical cross sectional view taken substantially on the line 2-2 of Figure 1, looking in the direction indicated by the arrows.

Figure 3 is a fragmentary detail view in horizontal cross section taken substantially

on the line 3-3 of Figure 1 looking in the direction indicated by the arrows.

Figure 4 is a view in elevation looking at the side of the holder into which the check is inserted.

Referring to the drawings in detail, it will be seen that the reference numeral 1 designates generally a housing or casing of any suitable material and, in the present instance, comprising a pair of complementary plates 2 which are clamped together in side abutting engagement and rigidly secured in position on a mine dump car by any suitable means such as the screws or the like 3 which are inserted through openings 4 provided therefor in the plates 2.

The opposed sides of the plates 2 are recessed to receive an arcuate inwardly and downwardly inclined check receiving chute 5 having its intake end communicating with one side of the housing or casing 1 adjacent the upper ends of said housing or casing as clearly illustrated in Figure 4 of the drawings. The outlet end of the check receiving chute 5 projects a slight distance into an intermediate portion of an inclined check receiving pocket 6 through the upper wall of said pocket 6. As clearly seen in Figure 2 of the drawings, the pocket 6 is of materially greater width than the chute 5. The pocket 6 is disposed at an inclination substantially opposite to the inclination of the chute 5 and has its open end projecting slightly into the upper portion of an angular check discharge chute 7 a portion of which is disposed vertically in the housing or casing 1 and a portion of which is disposed horizontally in the housing or casing 1 beneath the pocket 6. The lower wall of the horizontal portion of the discharge chute 7 is removed to permit a check to gravitate into the pivotally mounted retaining jaws 8 which are provided in the housing or casing 1 to prevent the check from being dropped to the ground and possibly lost when the

horizontal portion of the discharge chute 7 is removed to permit a check to gravitate into the pivotally mounted retaining jaws 8 which are provided in the housing or casing 1 to prevent the check from being dropped to the ground and possibly lost when the

car is dumped. The jaws 8 are provided with integral, opposed abutments 9 which are operable in the chamber 10 provided therefor in the housing or casing 1 in one of the plates 2 and a coil spring 11 is operatively engaged with the abutments for yieldingly urging the jaws 8 toward each other. The coil spring 11 and the abutments 9 are disposed adjacent one side of the horizontal portion of the discharge chute 7. The jaws 8 are pivotally mounted as at 12 on the plates 2 of the housing or casing 1. A check designated by the reference numeral 13 is shown retained between the jaws 8 in Figures 1 and 2 of the drawings.

In use, when the car is closed a check is inserted in the chute 5 and gravitates to the lower closed end portion of the inclined pocket 6 in the housing or casing 1. It is understood, of course, that, as before stated, the holder is rigidly mounted in vertical position at any desired point on the dump car. When the car is dumped the holder is disposed at an inclination which will cause the check to gravitate into the discharge chute 7 from the pocket 6 and from the discharge chute 7 the check drops between the retaining jaws 8 in the manner clearly illustrated in Figure 1. The check 13 is thus retained between jaws 8 until removed by hand from between said jaws. As will be readily apparent, the spring 11 permits the jaws 8 to be spread when removing the check 13 from therebetween. The end portion of the coin receiving chute 5 which projects into the pocket 6 prevents the check from re-entering the chute 5 from the pocket 6 at all times. It will also be obvious that the end portion of the pocket 6 which projects into the discharge chute 7 will prevent the check from re-entering the pocket 6 from the discharge chute 7 under all conditions. The check engaging portions of the jaws 8 are channeled or substantially U-shaped in cross section. It will also be seen that the discharge chute 7 is closed at its upper end.

It is believed that the many advantages of a holder constructed in accordance with this invention will be readily understood, and although the preferred embodiment of the invention is as illustrated and described, it is to be understood that changes in the details of construction may be had which will fall within the scope of the invention as claimed.

What is claimed is:—

1. A check holder comprising a casing for vertical mounting on a support, an inclined pocket mounted in the casing and closed at its lower end and open at its upper end, a check receiving chute disposed in the casing and having one end communicating with an intermediate portion of the pocket through the upper wall of the pocket, and a check discharge chute mounted in the casing, the

upper end portion of the pocket communicating with an upper portion of the discharge chute in a manner to discharge the check thereinto when the casing is moved from a vertical to an inclined position, and a pair of pivoted, spring controlled jaws disposed beneath the outlet end of the discharge chute to receive the check therefrom and releasably retain said check.

2. A check holder comprising a casing for vertical mounting on a support, an inclined pocket mounted in the casing and closed at its lower end and open at its upper end, a check receiving chute disposed in the casing and having one end communicating with an intermediate portion of the pocket through the upper wall of the pocket, and a check discharge chute mounted in the casing, the upper end portion of the pocket communicating with an upper portion of the discharge chute in a manner to discharge the check thereinto when the casing is moved from a vertical to an inclined position, and a pair of pivoted, spring controlled jaws disposed beneath the outlet end of the discharge chute to receive the check therefrom and releasably retain said check, the outlet end portion of the check receiving chute projecting into the check receiving pocket, and the open end portion of the check receiving pocket projecting into the discharge chute.

3. A check holder comprising a casing for vertical mounting on a mine dump car and including a pair of complementary plates rigidly secured together, an elongated, inclined pocket mounted between the plates and having its lower end closed and its upper end open, a check receiving chute extending at an inclination between the plates from one edge thereof and having one end projecting into an intermediate portion of the pocket through the upper wall of the pocket in a manner to discharge a check thereinto, an angular check discharge chute mounted between the plates and having a vertical portion and a horizontal portion, the open end portion of the pocket projecting into the vertical portion of the discharge chute, a portion of the lower wall of the horizontal portion of the discharge chute being removed for the discharge of the check, and a pair of complementary spring controlled jaws operatively mounted beneath the discharge chute to receive and retain the check therein.

4. A check holder comprising a casing having a pocket therein, a check receiving chute communicating with the pocket for delivering checks thereinto, a check discharge chute communicating with the pocket for receiving checks therefrom, and spring controlled means adjacent the outlet end of the discharge chute for receiving and releasably retaining the checks therein.

5. A check holder comprising a casing having a pocket therein, a check receiving chute communicating with the pocket for delivering checks thereto, a check discharge chute communicating with the pocket for receiving checks therefrom, and spring controlled means adjacent the outlet end of the discharge chute for receiving and releasably retaining the checks therein, said means including a pair of coacting jaws and a spring engaged with the jaws for yieldingly urging same toward operative position.

In testimony whereof I affix my signature.
JOSEPH DROPULICH.
